Primary Examiner — Sheryl Lane*Assistant Examiner* — Katherine Glennon(74) *Attorney, Agent, or Firm* — Wolf, Greenfield & Sacks, P.C.(57) **CLAIM**

The ornamental design for a display screen with graphical user interface, as shown and described.

DESCRIPTION

FIG. 1 is the first image in a sequence of a display screen with graphical user interface showing our new design according to a first embodiment.

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof; and,

FIG. 8 is the eighth image thereof.

The features shown in broken lines in the drawings depict environmental subject matter only and form no part of the claimed design. The subject matter in this patent includes a process or period in which an image changes into another image. The process or period forms no part of the claimed design.
